CASING OR SIMILAR ARTICLE FOR A PROTHROM-
BIN TIME DETERMINATION APPARATUS OR
THE LIKE

Gerald W. Wolfe, Bristol, Pa., assignor to Becton, Dickin-
son and Company, Rutherford, N.J., a corporation of
New Jersey

Filed Mar. 8, 1962, Ser. No. 69,151

Term of patent 14 years

(Cl. D16—2)

FIG. 1

FIG. 2

FIG. 3

FIG. 4

FIG. 1 is a front perspective view of a casing or similar article for a prothrombin time determination apparatus or the like showing my new design thereof;

FIG. 2 is a rear perspective view thereof;

FIG. 3 is a front perspective view of a casing or similar article for a prothrombin time determination apparatus or the like showing a modification of my new design thereof; and

FIG. 4 is a rear perspective view of FIG. 3.

The dominant features of my design are shown in solid lines in the drawings.

I claim:

The ornamental design for a casing or similar article for a prothrombin time determination apparatus or the like, as shown and described.
